[57] CLAIM

The ornamental design for hood protector, as shown and described.

DESCRIPTION

FIG. 1 is a front elevation of a hood protector embodying our new design;

FIG. 2 is a rear elevation thereof;

FIG. 3 is a top plan thereof;

FIG. 4 is a bottom plan thereof;

FIG. 5 is a left end elevation thereof, with the opposite end elevation being a mirror image thereof; and,

FIG. 6 is a cross-section thereof according to section line 6—6 of FIG. 1.
